(57) **CLAIM**

The ornamental design for a vehicle seat, as shown and described.

DESCRIPTION

FIG. 1 is a front, top and left side perspective view of a first embodiment of the vehicle seat showing our new design;

FIG. 2 is a rear, top and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is a referential view thereof showing the article in use;

FIG. 10 is a front, top and left side perspective view of a second embodiment of the vehicle seat showing our new design;

FIG. 11 is a rear, top and left side perspective view thereof;

FIG. 12 is a front view thereof;

FIG. 13 is a rear view thereof;

FIG. 14 is a top plan view thereof;

FIG. 15 is a bottom plan view thereof;

FIG. 16 is a right side view thereof;

FIG. 17 is a left side view thereof;

FIG. 18 is a referential view thereof showing the article in use;

FIG. 19 is a front, top and left side perspective view of a third embodiment of the vehicle seat showing our new design;

FIG. 20 is a rear, top and left side perspective view thereof;

FIG. 21 is a front view thereof;

FIG. 22 is a rear view thereof;

FIG. 23 is a top plan view thereof;

FIG. 24 is a bottom plan view thereof;

FIG. 25 is a right side view thereof;

FIG. 26 is a left side view thereof; and,

FIG. 27 is a referential view thereof showing the article in use.

The features shown in broken lines in the drawings depict environmental subject matter only and form no part of the claimed design.
